UNITED STATES PATENT OFFICE

2,195,207

EXPANSIBLE CHAMBER MOTOR

Wade H. Wineman, Michigan City, Ind., assignor
to Sullivan Machinery Company, a corporation
of Massachusetts

Application August 24, 1937, Serial No. 160,648

6 Claims. (Cl. 121—150)

My invention relates to expansible chamber motors, and, more particularly, to expansible chamber motors of the type which is especially adapted for pumping and like purposes.

At some oil fields a considerable quantity of oil is available, but the formation pressure is inadequate to raise the oil to the surface, and accordingly some type of pumping must be employed to enable recovery of the oil. Pumps located in the well and operated, through a sucker rod line extending to the surface, with steam or pneumatically operated, single-acting pumping motors, are very advantageous means for pumping such wells. A common and successful system employs a group of pumping motors for pumping a series of reasonably closely adjacent wells, with a central source of operating pressure fluid supply, and in such systems a single attendant may be sufficient for the entire group. However, he obviously cannot be at all the wells at the same time; and accordingly it is important that the pumping motors be as nearly completely automatic and free from possibility of derangement as possible. It is, therefore, desirable to avoid complexity in construction, to have no springs which may be subject to breakage, to avoid the use of small controlling valves for effecting or governing the operation of the main distributing valve, and to employ only simple and rugged parts.

It is an object of the present invention to provide an improved expansible-chamber motor. It is another object of my invention to provide an improved expansible-chamber motor having improved distributing valve means. It is a further object of my invention to provide an improved expansible-chamber motor having a distributing valve of very simple construction and which requires no auxiliary valves whatever for regulating its mode of operation. It is yet another object of my invention to provide an improved pumping motor having an improved distributing system in which a single valve controls the dual functions of admission and exhaust, and also, with the motor piston, is effective to provide for the proper movements thereof with comparatively long dwells in the admission and exhaust positions. Other objects and advantages of my invention will hereinafter more fully appear.

In the accompanying drawing, in which, for purposes of illustration, one embodiment which the invention may assume in practice is shown,

Fig. 1 is a side elevation of a pumping motor in which my invention is embodied in an illustrative form.

Fig. 2 is a central vertical section through the lower end of the motor cylinder and through the distributing valve mechanism, on a plane corresponding to the line 2—2 of Fig. 1.

Fig. 3 is an enlarged view on a similar plane 5 to that of Fig. 2, through the upper end of the distributing valve mechanism, showing the distributing valve in a different position.

Referring first to Fig. 1, it may be observed that suitable supporting means, of which a fragment 10 is shown at 2, carries a motor device 3 which comprises an upper head member 4, a lower head member 5, and a cylinder shell 6 which may be composed of one or more sections as desired. The cylinder 6 has a bore 7 in which a piston 8 is 15 reciprocable, and the piston 8 has a piston rod 9 which is adapted to be connected to a suitable pump rod or sucker rod line. The piston 8 is a single acting one, and is adapted to be raised by pressure fluid admitted beneath the same and 20 to be moved downwardly, upon a reduction in the pressure beneath its lower end, by the weight of the pump rod line, its own weight, etc. The lower cylinder head 5, which is connected to the upper head 4 by a series of tie rod devices 10, is provided with a valve chest and supply and discharge connection arrangement, generally designated 12. This comprises a motor fluid supply space 13 to which fluid is supplied through a supply connection 14. It also comprises an exhaust space 15 25 30 which is connected to an exhaust connection 16. The fluid supply may advantageously be at a pressure of two to three hundred pounds per square inch, although it will be appreciated that a very wide range of operating pressure is possible; and the exhaust connection is maintained by suitable means, not shown, under a back pressure which, for operating pressures of from two to three hundred pounds, may well be from fifty to one hundred pounds per square inch, the back pressure 35 used depending upon the operating conditions, and particularly upon depth of the well, the weight of the sucker rod line, etc. A connection 17 extends from a space 18, intermediate spaces 13 and 15, to the lower end of the bore of the 40 cylinder 7. The supply space 13 and the cylinder connected space 18 have between them a septum 19, and the exhaust space 15 and space 18 have a septum 20 between them. A suitable valve-chamber forming element 21, having a 45 stepped peripheral surface, is mounted in a series of bores of progressively decreasing sizes, 22, 23, 24, 25, and is provided with shoulders as at 26 adapted to seat upon supporting surfaces 27, or, preferably, upon intermediate gaskets 28 at 50 55

the junctions of certain of the stepped bores. A head 29 held in position by screws 30 is arranged opposite the lower end of the valve chest member 21, and has a reduced portion 31 which extends into a bore 32 which extends throughout something more than half the length of the valve chest member 21. It will be noted that the valve chest member is not a close fit at its lower end for the counterbore 33, which serves to provide a continuous connection between the exhaust space 16 and a space 34 surrounding the lower end of the reduced portion 31 of the head member 29. Passage means 35 connects the space 34 and the lower end of the bore 32. The bore 32 is connected by ports respectively numbered 36, 37 and 38 with the supply space 13, the cylinder connected space 18, and the exhaust space 15. The valve chest member 21 is provided in its upper end with an elongated larger bore 39 coaxial with the bore 32 and opening through the upper end of the valve chest member. An upper head 40 is held in any suitable manner, as by screws 41, in a position to close the upper end of the bore 39. Herein screws 41 also hold, through the head 40, the member 21 in position.

Within the bores 32, 39 there is reciprocable a distributing valve element 43 which may desirably be made of relatively light material and hollowed out to reduce its weight. This member comprises a lower, suitably ringed or otherwise packed head 44, fitting the bore 32, an intermediate, elongated, ringed portion 45 also fitting the bore 32, a narrow annular enlarged portion 46 fitting the bore 39, and an upper, longer, enlarged portion 47 also fitting the bore 39. Portions 46 and 47 are each appropriately ringed or otherwise packed. Portions 46 and 47 are separated by a reduced portion 48, which provides a fluid conducting groove 49 whose function will be more fully explained. Portions 44 and 45 are also connected by a reduced portion, this numbered 50; and as a result an annular space 51 is provided for fluid distribution purposes, selectively acting to connect the motor cylinder with the supply and exhaust spaces in the different positions of the distributing valve. Any suitable means may be provided, if desired, for example, a small stop boss 52, to prevent the possibility that the distributing valve 43 may stop or be made sluggish because of complete surface contact between its upper end and the inner side of the head 40.

The valve chest member 21 is provided herein with a conduit 55 extending longitudinally thereof and communicating at 56 at its upper end with the very top of the bore 39, while its lower end communicates at 57 with the bore 39 at a point opposite which, in the raised position of the distributing valve, 43, the groove 49 in the latter lies; and in the lower position of the distributing valve 43 the head 47 seals off with its median portion the port 57. Another port 58 opens through the wall of the valve chest member 21 at such a point that in the raised position of the valve it may be connected by the groove 49 with the port 57. In the lower position of the distributing valve communication is interrupted between the ports 57 and 58 by the lower part of the distributing valve head 47. A vent port 59 communicates with the bore 39 at the lowermost portion of the latter, and bleeds off any pressure which may leak past the rings in either direction along the valve member 43. Still another port 60 opens into the upper portion of the bore 39, communicating with the latter at such a position that it is sealed by the peripheral portion

of the head 47 in the raised position of the valve 43, but communicates freely with the space in the bore 39 above the top of the valve 43 in the lower position of the valve element 43. A conduit 61 connects the port 60 with the cylinder bore 7, at a point, 62, in the latter so located that it is uncovered by the upper end of the downwardly moving piston 8 only approximately as the desired lower limit of the piston stroke is reached. A conduit 64 connects the port 58 with the cylinder bore 7 at a point 65 so located that the upwardly moving piston passes above it only as the piston attains approximately to the desired upper limit of travel.

A suitable breather and protective device 66, 15 which forms the subject matter of my application Serial No. 102,987, is arranged in such position as to provide for the adequate cushioning of the piston 8 in the event of sucker rod line breakage or other mishap which would render the upward movement of the piston 8 uncontrolled. It also maintains the pressure above the piston 8 in the cylinder bore 7 at all times during normal motor operation, within a pound or two of atmospheric.

It will be understood that the distributing valve may be equipped with controlling mechanisms of the character shown and described in my applications, Serial No. 102,989, now Patent No. 2,156,326 dated May 2, 1939, and Serial No. 102,988, and portions of the latter mechanism are shown but not described herein, as they do not enter as an essential feature into the particular motor structure which I am making the subject of this application.

The mode of operation of the structure which has now been described will be readily understood. Assume the parts to be in the position shown in Fig. 2, with the motor piston 8 still moving downwardly and with the distributing valve 43 in the position to connect the cylinder through port 17, space 18, groove 51, ports 38, and space 15 with the exhaust line. The piston 8 has not yet gotten down far enough for its upper end to pass below the point 62. In the position of the parts shown, it will be appreciated that the lower end of the head 44 of the distributing valve 43 is subjected to motor back pressure—the pressure in the exhaust line—and that this is also true of the somewhat larger upper head 47 of the distributing valve 43, as the space within the cylinder bore below the piston 8 is connected through the connection 61 and port 60 with the space in the bore 39 above the head 47. Accordingly, the valve 43 is occupying its lower position, due to its weight and to the fact that its larger upper end is subjected to the same pressure as its smaller lower end.

When the piston 8 passes below the point 62, the space above the head 47 in the bore 39 will be connected through port 60, the connection 61, the cylinder bore 7, and the valve mechanism 66, with the atmosphere; and accordingly the pressure which has been acting upon the upper head of the piston 47 and holding the distributing valve 43 in its lower position will be reduced to atmospheric pressure; and the motor exhaust line pressure, which will continue to act through the space 15, clearance 33, annular space 34, and passage means 35, upon the lower end of the distributing valve head 44, will move the distributing valve from the position of Fig. 2 to the position of Fig. 3. This will cause the groove 51 to disconnect the cylinder port 17 from the exhaust space 15 and connect it to the supply space 75

13, with the result that motive fluid will be admitted beneath the piston 8 and start to raise the latter. This upward movement of the distributing valve 43 will also cause the upper head 47 of the distributing valve to seal off port 60. It will also cause the groove 49 to connect the port 58 and the port 57, and as a result the upper end of the bore 39 will be placed in communication with the connection 64, and accordingly, notwithstanding the fact that communication with the atmosphere through the port 60, passage 61 and the cylinder bore 7 is cut off immediately upon shifting of the valve 43, an atmospheric connection through connection 64 and cylinder bore 7 will be provided between the upper end of the distributing valve and the atmosphere until the top of the upwardly moving motor piston 8 passes above the point of connection 65. Accordingly any leakage along the head 47 would be prevented from building up a valve-throwing pressure.

It will be appreciated that as the motor piston 8 begins to move upwardly under the action of the motive fluid admitted to its lower end, it will very quickly close communication between the connection 61 and the cylinder bore, but this is immaterial, as communication between the cylinder bore and the valve receiving bore 39 has already been interrupted by the raised distributing valve 43. As the piston 8 moves a little farther up, its lower end will pass above the point of connection 62, and fluid will enter, at cylinder pressure, the connection 61 and pass to the port 60, but will be blocked from entering the valve chest by the lateral surface of the head 47. Accordingly, since the valve 43 will remain in its position to admit fluid beneath the piston 8, the latter will continue its upward movement until its lower end passes above the connection point 65. Thereupon cylinder pressure will pass through the connection 64 and port 58 into the bore 39 and through the groove 49 into the port 57, and through the passage 55 and port 56, and enter the top of the valve chest bore 39 and act upon the top of the distributing valve head 47 and force the distributing valve 43 back to the position shown in Fig. 2. Thereupon, with motive fluid supply cut off and with a renewed connection between the cylinder bore, through passage 17, groove 51, and exhaust space 15, established with the exhaust line, the motor piston 8 will start downwardly. It will be observed that in the position shown in Fig. 2, the port 60 has been uncovered, and accordingly a connection between the portion of the cylinder bore 7 below the motor piston 8 and the space above the distributing valve head 47 will be established and maintained throughout most of the downward movement of the motor piston, and as the motor cylinder pressure will not be less than motor back pressure, and as the motor cylinder pressure will continue to be maintained, through the connection 61 and port 60, in the space above the distributing valve head 47, the latter will be maintained in its lower position notwithstanding the fact that the cylinder pressure will be reduced by the opening of the exhaust connection, because equal pressure materially above atmospheric will be acting on the larger upper and smaller lower ends of the distributing valve, and there will also be the weight of the valve tending to hold it in its lower position. It will be noted, also, that the movement of the distributing valve to the position shown in Fig. 2 will have interrupted communication of

the connection 64 with the upper end of the space 39 and, as it were, have sealed the port 53.

As the motor piston 8 continues its downward movement, the distributing valve 43 will remain in its position of Fig. 2 until the upper end of the downwardly moving piston 8 passes below the connection point 62, and thereupon the distributing valve will be again thrown to the position of Fig. 3, due to the venting through the port 60, connection 61, and the cylinder bore 7, of the pressure which had been acting on the top of the valve head 47.

The further operation of the motor will be a repetition of the cycle which has been described.

It will be noted that the structure which has been described is very simple; involves no auxiliary valves, either check valves or pilot valves; comprises parts which may be made large and strong but yet light; that the porting necessary for the control of the distributing valve is extremely simple; that a long stroke may be obtained very easily and yet the valve may be held positively in its different positions during the relatively long piston movements; and that, practically speaking, there is nothing which can get out of order in the construction which has been described.

While there is in this application specifically described one form which the invention may assume in practice, it will be understood that this form has been shown for purposes of illustration, and that the invention may be modified and embodied in various other forms without departing from its spirit or the scope of the appended claims.

What I claim as new and desire to secure by Letters Patent is:

1. In a distributing valve mechanism for a motor cylinder, a valve chest, motive fluid supply, exhaust and cylinder connections leading thereto, said exhaust connection having continuously maintained therein a superatmospheric pressure, a valve in said chest, throwing means for said valve including oppositely facing, unequal pressure areas thereon, means for continuously subjecting one of said areas to the pressure in said exhaust connection, means for intermittently subjecting the other of said areas to line pressure, exhaust pressure and atmospheric pressure, including conduits connecting said cylinder with said valve chest at points overrun by said valve in its movements, and means including a passage of which at least a part lies in the walls of said valve chest for connecting one of said conduits with the end of said valve chest adjacent said last mentioned pressure area when said valve is in one of its limiting positions.

2. In a distributing valve mechanism for a motor cylinder, a valve chest, motive fluid supply, exhaust and cylinder connections leading thereto, said exhaust connection having continuously maintained therein a superatmospheric pressure, a valve in said chest for controlling admission to and exhaust from said motor cylinder, throwing means for said valve including oppositely facing, unequal pressure areas thereon, means for continuously subjecting the smaller of said areas to the pressure in said exhaust connection, means for intermittently subjecting the larger of said areas to line pressure, exhaust pressure and atmospheric pressure, including a pair of conduits connecting said cylinder with said valve chest at points spaced longitudinally of the latter, and means including a passage formed at

least in part in the walls of said valve chest for connecting one of said conduits with the end of said valve chest adjacent said last mentioned pressure area when said valve is in its admission-effecting position.

3. In a distributing valve mechanism for a motor cylinder, a valve chest, motive fluid supply, exhaust and cylinder connections leading thereto, said exhaust connection having continuously maintained therein a superatmospheric pressure, a valve in said chest for controlling admission to and exhaust from said motor cylinder, throwing means for said valve including oppositely facing, unequal pressure areas thereon, means for continuously subjecting the smaller of said areas to the pressure in said exhaust connection, means for intermittently subjecting the larger of said areas to line pressure, exhaust pressure and atmospheric pressure, including a pair of conduits connecting said cylinder with said valve chest at points spaced longitudinally of the latter, a passage having spaced ends in the walls of said valve chest for connecting the end of said valve chest adjacent said last mentioned pressure area with a point in said valve chest between said conduits, and a groove on said valve, said groove connecting one of said conduits with said passage when said valve is in one of its limiting positions.

4. In a motor, in combination, a cylinder having means for venting one end thereof, a piston reciprocable in said cylinder, a motive fluid supply line, an exhaust line having continuously maintained therein a superatmospheric back pressure, a valve mechanism for said motor for connecting the other end of the motor cylinder alternately to said supply line and to said exhaust line, said valve mechanism including a valve and controlling means therefor including means forming a pressure chamber and means movable in said chamber and having a pressure area acting when subjected to cylinder working pressure to move said valve, means for controlling the supply of such pressure to said area, and the venting of such pressure therefrom including conduits having their extremities remote from said area opening into communication with the cylinder bore at points widely spaced longitudinally of the latter but each covered and also uncovered by each end of the piston during each complete cycle of piston movement and having their other ends opening into said pressure chamber at points spaced longitudinally of the latter, and means including a passage having opposite ends in the walls of said chamber for connecting one of said conduits with said pressure area when said valve is in its cylinder-supply-connecting position.

5. In a motor, in combination, a cylinder having means for venting one end thereof, a piston reciprocable in said cylinder, a motive fluid supply line, an exhaust line having continuously maintained therein a superatmospheric back pressure, a valve mechanism for said motor for connecting the other end of the motor cylinder

alternately to said supply line and to said exhaust line, said valve mechanism including a valve and controlling means therefor including means forming a pressure chamber and means movable in said chamber and having a pressure area acting when subjected to cylinder working pressure to move said valve, means for controlling the supply of such pressure to said area and the venting of such pressure therefrom including a pair of conduits having their extremities remote from said area opening into communication with the cylinder bore at points widely spaced longitudinally of the latter but both covered and also uncovered by each end of the piston during each complete cycle of piston movement and having their other ends opening into said pressure chamber at points spaced longitudinally of the latter, a passage at least a portion of which lies in the walls of said chamber for connecting a point in said pressure chamber between said conduits with the space at the end of said chamber adjacent said pressure area, and groove on said valve for connecting one of said conduits with said passage when said valve is in its cylinder-supply-connecting position.

6. In a motor, in combination, a cylinder having means for substantially freely venting one end thereof continuously during normal motor operation, a piston reciprocable in said cylinder, and means for alternately supplying operating fluid to the working end of said motor cylinder and connecting the latter with exhaust including a valve chest, motive fluid supply, exhaust and cylinder connections leading thereto, said exhaust connection having continuously maintained therein a superatmospheric back pressure, a valve member in said chest and throwing means for said valve member including oppositely facing unequal pressure areas thereon, means for continuously subjecting one of said areas to a pressure sufficient to throw said valve member when the pressure upon the other of said areas is reduced below a predetermined value and means for intermittently subjecting the other of said areas in turn to cylinder working pressure, to cylinder exhaust pressure, and to substantially atmospheric pressure including conduits connected at one end to said valve chest at points spaced longitudinally thereof and at their other ends opening into communication with the cylinder bore at points widely spaced longitudinally of the latter but each covered and also uncovered by each end of the piston during each complete cycle of piston movement, a groove on said valve member and passage means extending longitudinally of said valve chest and relative to which said valve member is longitudinally movable and cooperating with said groove in one position of said valve member to connect the conduit whose communication with the cylinder is then later uncovered by the working end of the piston during the working stroke thereof, with said last mentioned valve throwing area.

WADE H. WINEMAN.

CERTIFICATE OF CORRECTION.

Patent No. 2,195,207.

March 26, 1940.

WADE H. WINEMAN.

It is hereby certified that error appears in the printed specification of the above numbered patent requiring correction as follows: Page 4, second column, line 60, claim 6, for "then later" read --the later--; and that the said Letters Patent should be read with this correction therein that the same may conform to the record of the case in the Patent Office.

Signed and sealed this 10th day of September, A. D. 1940.

(Seal)

Leslie Frazer,
Acting Commissioner of Patents.
